ABSTRACT: Energy emitted in a rearward direction from vibratory energy transducers is conveyed from the rear end of a transducer to another by coupling members of equal length joining similar portions of the rear ends of the transducers.

In the preferred embodiment the coupling members are of steel rods and are stranded in the form of steel rope without a central crown rod.

VIBRATORY ENERGY GENERATORS

This invention relates to vibratory energy generators.

With vibratory energy generators in the form of magnetostrictive and piezoelectric transducers, vibratory energy is propagated in a rearward direction as well as in the forward direction in which the energy is required. Usually this rearward-propagated energy is dissipated in a mass of metal or other material and so is not usefully employed. In fact, in, for example, sonic transducers used for echo sounding this rearward-propagated energy can be a nuisance if a large proportion of it is not dissipated because it may result in spurious echos.

It is an object of the present invention to usefully employ rearwardly propagated energy in a vibratory energy transducer.

According to the present invention there is provided a vibratory energy generator, comprising a plurality of similar vibratory energy-producing transducer elements disposed side by side with each said element having a forward vibratory energy-propagating surface facing the generator-transmitting direction, and a rearward vibratory energy-propagating surface, a plurality of vibrating energy-conveying coupling members joining said rearward surfaces to another, whereby rearwardly propagated energy from each said element will be transferred to another said element to be emitted from the latter element from the forward surface thereof in the direction and in phase with the forward-propagated energy from that element.

In the accompany drawing which illustrates, by way of example, an embodiment of the present invention there is shown two transducing elements of a vibratory energy generator.

In the drawing there is shown two vibratory energy-producing transducing elements 1 and 2 of a vibratory energy generator mounted in a nodal plate 3 and secured at their forward vibratory energy-propagating surfaces by heads 9 to a diaphragm 4. The elements 1 and 2 are provided with tails 5 and 6 respectively which are joined by a plurality of vibratory energy conveying coupling members generally designated 7. The coupling members 7 are substantially rigid steel rods stranded together in a helical fashion without a center crown rod. Each rod is stranded to have one complete helical turn so that it connects corresponding areas of each tail 5 and 6 together. Thus, a rod 8 joins a right-hand portion of tail 5 to a corresponding right-hand portion of tail 6. The coupling members 7 are equal in length and the inner layers of rods are each given a more acute helix angle, the closer they are to the center for this purpose. The coupling members 7 may be touching but are sufficiently loosely wound together to allow relative movements between them. Being of a substantially rigid material such as steel the rods are circular in cross section. If they were of a less rigid material such as copper the cross section would then have to be larger in diameter or rectangular to impart rigidity to them. The rigidity would be imparted by the longer sides of the rectangle extending from left to right in the drawing where the coupling members 7 are joined to the tails 5 and 6.

In operation the elements 1 and 2, which may be magnetostrictive, piezoelectric or any other electromechanical elements, are energized to impart vibratory energy by their forward vibratory energy-propagating surfaces to the diaphragm 4. Each rearward vibratory energy-propagating surface propagates vibratory energy in a rearward direction which is at the same frequency and in phase with the energy propagated from the forward vibrating energy-propagating surface. The coupling member lengths are $N\lambda$ where N is an integer and λ is the wave length of the vibratory energy being generated so that a substantial proportion of the rearwardly propagated vibratory energy is conveyed from each rearward surface to the other. Thus rearwardly propagated vibratory energy from each element 1 and 2 is transferred from one element to another to be emitted from the latter element from the forward surface thereof in the direction and in phase with the forward-propagated energy from that element and hence substantially eliminating the rearward propagation of vibratory energy therefrom.

It is essential that the coupling members 7 cover substantially the whole of the rearward surfaces of the elements 1 and 2. To this end it may be desirable to thicken the end portions of coupling members 7 in the shape of an elephant's foot.

It is also essential that the coupling members be connected, by for example an adhesive such as epoxy resin, welding or brazing, at right angles to the rearward surface with respect to their longitudinal axis at the joint. Furthermore sharp corners on the coupling members should be avoided as reflected vibrations will be produced at sharp corners.

The lengths of the tails 5 and 6 may have to be adjusted to suit the frequency of the vibrations, in combination with the coupling members.

15 The coupling members may be of any material which will convey the vibratory energy provided it is sufficiently rigid not to flex, steel is an ideal material but nickel, copper or other materials may be used. If desired the coupling members may be coated with a material such as which will act as a lubricant 20 and assist relative movements between the coupling members 7.

25 The coupling members 7 may be helically wound with one complete turn or in multiples of complete turns so that corresponding areas of each element 1 and 2 joined to one another.

Whilst two elements 1 and 2 are shown joined to one another, any number of elements may be coupled in pairs in this manner. Where three elements are used they may be disposed as at the points of a triangle so that one half of each element can be coupled to a corresponding half of another element. Thus all of the elements are coupled to one another in this embodiment.

35 There will inevitably be some reflections at the joints between the coupling members 7 and the tails 5 and 6. Furthermore as vibratory energy is travelling in both directions along the coupling members 7 there will be some cancelling out effect. However, these losses will be small.

40 It will be appreciated that the underneath layers of coupling members 7 may be wound in the same or opposite direction to that of the outer layer. The coupling members need not be wound together but may be splayed in order not to foul one another, however, it is preferred that they are wound together as this is a more compact arrangement.

45 The vibratory energy generators having coupled transducing elements may be used in many applications such as, for example, sonar detection, welding, machining, cleaning, piling and agitation, cavitation or boiling.

I claim:

50 1. A vibratory energy generator, comprising a plurality of similar, vibratory energy-producing transducer elements disposed side by side, with each said element having a forward vibratory energy-propagating surface facing the generator-transmitting direction and a rearward vibratory energy-propagating surface, a plurality of substantially rigid vibrating energy-conveying coupling members each $N\lambda$ in length where N is an integer and λ is the wave length of the vibratory energy to be propagated, said coupling members joining substantially the whole of said rearward surfaces to convey rearwardly propagated energy from one said rearward surface to another, whereby rearwardly propagated energy from each said element will be transferred to another said element to be emitted from the latter element from the forward surface thereof in the direction and in phase with the forward-propagated energy from that element.

60 2. A generator as claimed in claim 1, wherein said coupling members comprise for each said element a plurality of substantially rigid metal loops, all of said loops forming vibratory energy-conveying paths of equal length with substantially no vibratory energy-reflecting surfaces therealong.

3. A generator as claimed in claim 2, wherein said coupling members are helically wound together.

4. A generator as claimed in claim 1, wherein tail members are interposed between the said coupling members and the said elements.
